CLAIM

We claim the ornamental Design for an ergonomic disposable plate bottom, as shown and described.

DESCRIPTION

FIG. 1 is a perspective view of an ergonomic disposable plate bottom;

FIG. 2 is a front elevation view of the plate of FIG. 1, with an opposite view being identical thereto;

FIG. 3 is a side elevation view of the plate of FIG. 1, with an opposite view being identical thereto;

FIG. 4 is a top plan view of the plate of FIG. 1;

FIG. 5 is a bottom plan view of the plate of FIG. 1;

FIG. 6 is a cross-sectional front view of the plate of FIG. 1, with an opposite view being identical thereto;

FIG. 7 is a cross-sectional side view of the plate of FIG. 1, with an opposite view being identical thereto; and,

FIG. 8 is a perspective view of a second embodiment thereof.

The broken lines in the drawings are for illustrative purposes only and form no part of the claimed design.
